UNITED STATES PATENT OFFICE.

WILLIAM T. GULLEDGE, OF MATTHEWS, NORTH CAROLINA

JACK.

Application filed February 21, 1922. Serial No. 538,261.

To all whom it may concern:

Be it known that I, WILLIAM T. GULLEDGE, a citizen of the United States, residing at Matthews, in the county of Mecklenburg and 5 State of North Carolina, have invented certain new and useful Improvements in Jacks, of which the following is a specification.

My invention relates to jacks and has particular reference to a combination tire rim 10 and vehicle jack, the primary object being the provision of a simple device which is readily adaptable to engage a tire rim for tire mounting purposes, or to be used in the ordinary way as a vehicle jack.

Another object of the invention is to provide in a jack of this character novel means for reversing the direction of the travel of 15 the plunger and also novel means for locking the plunger in any position as desired.

A further object of the invention is to provide in a jack of this character, novel pawl and ratchet mechanism to assist in the accomplishment of the purpose outlined.

With these and such other objects in view 20 as will be apparent from the description, my invention resides in the novel construction, combination and arrangement of parts hereinafter described and claimed, and illustrated in the accompanying drawings, of 25 which

Figure 1, a vertical section of an embodiment of the invention;

Figure 2, a vertical section taken at right angles to Figure 1;

Figure 3, a top plan view; and

Figure 4, a horizontal section on the line 10—10 of Figure 2.

In detail the invention comprises a plunger 30 consisting of a rotatable screw threaded member disposed longitudinally of a casing 20 and engaged at the outer end of the casing through a plate 21 apertured at its center and interiorly threaded to receive therethrough the plunger, whereby when 45 rotary movement is imparted to the plunger the same will be carried through the plate in an obvious manner. The extreme inner end of the plunger is provided with a squared portion 31, and the portion of the 50 plunger directly adjacent thereto is devoid of threads for a space, as indicated at 32, for a purpose hereinafter described. A gear wheel 33 is mounted on the squared end of the plunger, being suitably secured thereto, 55 and carrying an enlarged ratchet wheel 34.

In this construction the casing is open at

one side and disposed through its open side is an operating handle 35 pivoted at its inner end on the rounded portion 32 of the plunger and carrying a double-ended pawl member 37 to engage the teeth of ratchet wheel 34, whereby upon movement of the handle rotation will be imparted to the ratchet wheel and plunger upon which, owing to the threaded engagement of the 60 upper end of the plunger with the plate 21, the plunger will be moved longitudinally of the casing. A reversal of the pawl will accomplish a reverse movement of the plunger, as is obvious. The mounting of the 65 pawl is similar to the mounting of the pawl described in the preferred form of the invention and it is not deemed necessary to refer specifically to the mounting of the 70 parts.

In this embodiment of the invention, the casing is provided with a longitudinal slot 38, in one side, and disposed in this slot is a slidable bar 39 carrying an axle supporting bracket 40, extending through the slot 80 at the side of the casing, and beyond the end plate 21 of the casing the bar is bent laterally and apertured at its free end 41 to rest over and engage the outer end of the plunger 30, which is provided with a shoulder 85 42, at this point. By this construction, it is obvious that when the plunger is moved longitudinally of the casing the bar 39, and consequently the bracket 40, will be carried 90 therewith.

While I have described and illustrated certain forms and details and materials which enter into the construction and operation of my invention, I desire it to be understood that I do not intend to limit 95 myself to these, but that any such may be used as will fall within the scope of the invention as claimed.

I claim:

1. A jack of the character described comprising a casing, an end plate in said casing provided with an internally threaded bore therethrough, a screw-threaded plunger threaded in said bore for supporting engagement with said plate, a ratchet wheel secured 100 on the opposite end of said plunger, an operating handle pivoted over said plunger and adjacent said ratchet wheel, a pawl member carried by said operating handle and adapted to engage said ratchet wheel, 105 whereby rotation is imparted through said wheel to the plunger, one side of said casing 110

being open to receive therethrough said operating handle.

2. A jack of the character described comprising a casing, an end plate in said casing and having a threaded bore therethrough, a screw-threaded plunger rotatably disposed in said bore and adapted to extend through said plate, pawl and ratchet mechanism carried by the inner end of said plunger, an operating handle for said pawl and ratchet mechanism, said handle extending through

one side of the casing, one wall of said casing being slotted, a bar slidably disposed in said slot and extending through the plunger end of said casing, said bar being connected 15 to the outer end of said plunger for movement therewith, and a vehicle supporting member carried by said bar and extending laterally of the casing through said slot.

In testimony whereof I affix my signature. 20

WILLIAM T. GULLEDGE.
